J. R. MASON

CONTROL MECHANISM

Filed Dec. 14. 1921

Fig. 1

UNITED STATES PATENT OFFICE.

JOHN R. MASON, OF CHICAGO, ILLINOIS, ASSIGNOR TO THE MOSES-ROSENTHAL COMPANY, OF CHICAGO, ILLINOIS, A CORPORATION OF ILLINOIS.

CONTROL MECHANISM.

Application filed December 14, 1921. Serial No. 522,301.

To all whom it may concern:

Be it known that I, JOHN R. MASON, a citizen of the United States, residing at 913 West Van Buren Street, Chicago, in the county of Cook and State of Illinois, have invented a new and useful Improvement in Control Mechanism, of which the following is a specification.

My invention relates to mechanism controlling the driving of one member from another and involving an element which is movable against a normally acting force, to effect driving connection between such members, and more especially where such element in its movement to different positions, effects the acceleration of the speed at which the driven member is driven, I having devised my invention for use, more particularly, in connection with treadle-controlled power-driven sewing machines, such as are commonly used in garment factories.

As control mechanisms, especially for sewing machines, have hitherto been provided, the operator is required at all times during the driving of the driven member from the drive member; to exert a force in opposition to the force which tends to disconnect the driven member from the drive member and this condition presents great disadvantages, especially in connection with treadle-controlled sewing machines, which, during the greater part of their operation, are operated at the highest speed attainable from the drive member. It has been found that in garment-making factories, where the operators operate the sewing machines for many hours at a time, that the operating of the controlling treadles tires the operators to such an extent that the operators are often incapacitated for continuous work and toward the end of the day often operate the machines at a much reduced speed, as compared with the maximum speed, with consequent inefficiency and reduced output. Furthermore, the constant pressure required to be overcome by the operator in maintaining the machines in operation, has a tendency, particularly toward the end of the day's work, to render the controlling of the speed at which the machine is driven, less accurate than would be the case if the condition above stated did not exist.

My primary object is to provide improvements in controlling mechanism, whereby when the mechanism is operated to a posi-

tion causing the machine to run at full speed, the control mechanism becomes releasably locked in such position and does not require application by the operator of continuing force, but which may be readily actuated by the operator to released condition, and where, as in the case of a sewing machine, provision is made for driving the driven element at varying speeds, depending upon the amount of pressure applied by the operator, the operator upon release of the holding mechanism referred to may accurately control the speed at which the driven element is operated from the driving element, all to the end of rendering the operator more efficient, relieving the operator from undue strains and tiring effects, and insuring the production of a better product and effecting greater economy in the production of the same.

Referring to the accompanying drawing; Figure 1 is a view in end elevation of mechanism for driving a sewing machine from a continuously operating power device and in which my invention is incorporated; and Figure 2, a broken view in side elevation of a portion of the mechanism shown in Fig. 1.

The particular illustrated embodiment of my invention shows it as incorporated in a power driven sewing machine comprising a transmitter commonly known as a "Union special belt adjusting power transmitter," and through which the drive of the sewing machine proper represented at 101 is effected from a source of power, shown as a drive pulley 10.

The transmitter shown, and of the specific construction above referred to, is represented at 13 and is formed of a stationarily supported shaft 100 on which the stepped pulley 12, formed of the two united pulley sections 12^a and 12^b, and the pulley 200, are journaled, the pulley 12 being slidable lengthwise of the shaft 100 toward and away from the pulley 200. The pulley 12 is driven by a belted connection 11 with the pulley 16, this belt engaging either of the pulley sections 12^a or 12^b, as desired, and furnishing a constant driving connection between the pulley 12 and the pulley 10. The drive of the sewing machine proper 101 is through the medium of a belt 201 engaging the pulley 200, the pulley 200 being driven from the pulley 12 by means of tapered friction clutch surfaces provided on these two pulley mem-

bers and adapted to frictionally engage by sliding the pulley 12 toward the pulley 200 against the action of a spring tending to hold these pulleys out of driving engagement with each other. The driving engagement between the pulleys 12 and 200 is controlled by a lever 14 pivoted at 14^a on a relatively stationary part of the machine, this lever being shown, in the drawings, in normal position in which the sewing machine proper 101 is at rest. When the lever 14 is rocked in counterclockwise direction in Fig. 2, it forces the pulley 12 into engagement with the pulley 200 at the friction surfaces referred to, thereby causing the sewing machine proper 101 to be driven, the speed at which the latter is operated depending upon the position to which the lever 14 is depressed, all as is well known in the art and, therefore, further detailed description of the transmitter mechanism and its manner of operation is unnecessary.

In the particular construction shown, the lever 14 is pivotally connected at its outer end with the upper end of a rod 15 preferably formed of sections 16 and 17 extending in parallel relation and adjustable lengthwise of each other and held together in adjusted position by a collar 18 provided with set screws 19 for engaging these rod sections, the lower end of the rod section 17 being pivotally connected with a lever 20 between the ends of the latter, as indicated at 21, one end of the lever 20 being fulcrumed at 22 on a bracket 23 depending from the platform 24 on which the sewing machine proper 101 is supported. The other end of the lever 20 is pivotally connected at 25 with one end of a toggle 26, the sections 27 and 28 of which are pivotally connected together at their adjacent ends by a pivot pin 29, the upper end of the toggle being pivotally connected at 30 with a bracket 31 secured to the underside of the platform 24. The pivot 29 is located at a point in the rear of a line drawn through the pivots 25 and 30, considering the toggle in fully extended position as represented by the dotted lines in the drawing, and the inner abutting end-surfaces 32 of the sections 27 and 28 extending preferably at substantially a right angle to the longitudinal planes of these sections, whereby these end-surfaces 32 form stops limiting the movement of the sections 27 and 28 relative to each other in the application of force thereto, tending to straighten the toggle. The section 28 of the toggle is pivotally connected with the upper end of a rod 33, the lower end of which is pivotally connected with the rear end of a treadle 34 pivoted between its ends, at 35, on a bracket 36 rising from the floor, represented at 37. The rod 33 is preferably formed of two rod sections 38 and 39, which extend parallel with each other and are lengthwise adjust-

able for varying the effective length of the rod 33, in collars 40 with set screws 41 surrounding the rod sections and holding them together in adjusted position. The connection of the rod 33 with the toggle is preferably at a sleeve 42, adjustably mounted on the toggle section 28, a set screw 43 being provided for clamping the sleeve in adjusted position on this toggle section, and with which sleeve the upper end of the rod section 38 pivotally engages, as indicated at 44.

In the normal position of the parts, namely when the lever 14 is in uppermost position and the sewing machine proper 101 driven through the transmitter, is at rest, the parts occupy the position shown in full lines in the drawing, these parts being held in this position by the spring tension resisting the depression of the lever 14. To effect driving connection between the drive element 10 and the sewing machine proper 101, the operator, whose foot rests upon the treadle 34, rocks the latter in counter-clockwise direction in the drawing with the result of causing the toggle 26 to swing toward straightened position, thereby rocking the lever 20 downwardly and drawing down on the lever 14, which so conditions the transmitter that drive of the sewing machine proper 101 is established, the speed at which the latter is driven depending on the extent to which the lever 14 is lowered in the operation stated. To drive the sewing machine proper 101 at the maximum speed, the operator rocks the treadle 34 in the direction stated to a position in which the toggle assumes the straight condition shown by the dotted lines in the drawing, in which position the stop surfaces 32 abut. In thus actuating the toggle, the pivot 29 is moved rearwardly of a line passing through the pivot points 25 and 30 and thus the control mechanism becomes automatically locked in the dotted position shown in the drawings and maintains maximum drive of the sewing machine 101 without requiring the exertion of continuing pressure by the operator against the treadle. The toggle, however, may be readily operated to move the pivot 29 forwardly of the line connecting the pivots 25 and 30 by the operator exerting an upward thrust on the rod 33, which may be accomplished by rocking the treadle 34 in clockwise direction in the drawing, and as soon as the pivot 29 has moved forwardly of the line referred to, the spring tension exerted by the transmitter on the lever 14, tending to move the latter to normal position, returns all of these parts to this position except as restrained by the operator in pressing against the treadle 34 in the opposite direction. From the foregoing it will be noted that the operator has complete control over the drive of the sewing machine for driving it at any desired speed, and that during

the driving of the sewing machine at maximum speed no force is required to be exerted by the operator in maintaining such speed.

5 It will be noted that by providing the adjustment in the rod 15, the maximum speed at which the sewing machine proper is operated may be varied, as desired.

While I have illustrated and described my

10 invention as applied to a particular kind of machine and have shown and described a particular embodiment of my invention, I do not wish to be understood as intending to limit it thereto, as it may be applied to other 15 machines and may be provided in various other forms, without departing from the spirit of my invention.

What I claim as new and desire to secure by Letters Patent, is:

20 1. The combination of a driving element, a driven element, means transmitting power from said driving element to said driven element and involving a movable member controlling the drive, means tending to move 25 said member to one position, and means for moving said member in opposition to said second-named means comprising a treadle, a toggle pivotally supported at one end, a pivotally supported lever connected beyond its 30 pivotal support with the outer end of said toggle, said member operatively engaging said lever, and a connection between said treadle and said toggle between the points of its pivotal support and its connection with 35 said lever, said toggle being so constructed and arranged that when actuated to extended condition it remains in such condition until force is reversely applied thereto.

2. The combination of a driving element, 40 a driven element, means transmitting power from said driving element to said driven element and involving a movable member controlling the drive, means tending to move 45 said member to one position, and means for moving said member in opposition to said

second-named means comprising a treadle, a toggle through the medium of which said member is actuated, and a toggle-operating link engaging one of the sections of said toggle between the ends of said section, said toggle being so constructed and arranged that when actuated to extended condition it remains in such condition until force is reversely applied thereto.

3. The combination of a driving element, 55 a driven element, means transmitting power from said driving element to said driven element and involving a movable member controlling the drive, means tending to move 60 said member to one position, and means for 65 moving said member in opposition to said second-named means comprising a treadle, a toggle pivotally supported at one end and through the medium of which said member is actuated, and a toggle-operating link 70 engaging one of the sections of said toggle between the ends of said section, said toggle being so constructed and arranged that when actuated to extended condition it remains in such condition until force is reversely applied thereto.

4. The combination of a driving element, 75 a driven element, means transmitting power from said driving element to said driven element and involving a movable member controlling the drive, means tending to move 80 said member to one position, and means for moving said member in opposition to said second-named means comprising a treadle, a toggle through the medium of which said member is actuated, and a toggle-operating link 85 engaging one of the sections of said toggle between the ends of said section, said toggle being so constructed and arranged that when actuated to extended condition it extends in a plane at an angle to said link and remains in such condition until force is reversely applied thereto.

JOHN R. MASON.
